UNITED STATES PATENT OFFICE

2,038,061

BRAUN TUBE

Kurt Schlesinger, Berlin, Germany

Application August 4, 1932, Serial No. 627,441
In Germany August 10, 1931

2 Claims. (Cl. 250—27.5)

When employing Braun tubes filled with a gas of suitable pressure, operated with an anode voltage of more than 1000 volts and working with ray currents of more than 10^{-4} amperes, more particularly for television purposes, distortions have been found to occur which, by reason of their practically regular occurrence in adjacent lines, must be laid down to oscillating charges in the glass wall which form between the screen and the deflecting elements. These distortions assert themselves in part in the form of undulatory deflections vertical to the movement of the beam (fringing). Distortions, however, have also been ascertained in the direction of the beam, making themselves apparent in the form of small nodules on the luminous screen. An example of fringelike distortion is illustrated in Fig. 1. In this there is shown the luminous screen of a Braun tube, on which screen the cathode ray traces the rectangular image produced by a television transmitter. Whereas at certain points 1 of the path of the ray no distortion takes place, the disturbing fringing action is found at other points.

These distortions, as already stated above, are to be laid down to oscillating glass wall charges, which are controlled in undesired fashion, probably by electrode or external fields. According to the invention in Braun tubes of the above mentioned kind the ions forming these charges shall either immediately be leaked off or retained by suitable means. For the purpose of leaking-off it is convenient to employ a metallic coating which is applied to the inside of the glass wall and is connected with an adapted potential, for example, with earth, or for retaining purposes a coating which is applied to the outer wall and is also conductively connected with earth or another constant potential. The disturbances made themselves apparent more particularly in the case of high anode potentials, 1000-4000 volts, and strong ray currents of the order of 10^{-4} amperes or more.

The form of the leaking or retaining coating is decided in part by the form of the glass wall, and therefore preferably constitutes part of a cylinder. As experiments have shown, both an annular portion of this kind as well as two oppositely disposed sections of such a ring are found suitable. When employing two of these sections, it has been found particularly convenient to place these opposite to each other in the direction of the disturbing deflections, and to connect the same with each other in conductive

fashion. Since the disturbing distortions occur in the direction of the oppositely situated adjacent deflecting plates, it has proved to be convenient to arrange the leakage plates parallel to the adjacent deflecting plates. The invention is set forth more precisely in conjunction with a few possible forms of embodiment.

In Fig. 2, 3 is a Braun tube having two pairs of deflecting plates 4 and 5, the Wehnelt cylinder 6, the cathode 7 located therein and the socket 8. 9 is the luminous screen on which the disturbing fringing action makes itself apparent. By the provision of the ring 10, and taking the same to earth, it is possible, as stated above, to prevent the disturbing effects. In Fig. 3 there is illustrated the same arrangement having two partly annular electrodes 11; the remaining parts are designated by the same reference characters as in Fig. 2. The electrodes 10 or 11 may be arranged inside the glass tube. It has been found yet more suitable to situate them on the exterior of the glass wall.

I claim:

1. A Braun tube comprising an envelope, a gas filling within said envelope, a cathode and an anode mounted in cooperative relation in said envelope for producing a cathode beam in the order of at least 10^{-4} amperes, two pairs of deflecting plates, a picture receiving screen and two electrodes, each consisting of a thin metallic coating, said electrodes forming parts of an annulus and being mounted on the inner side of the wall of said envelope between said deflecting plates and said screen for preventing the occurring of fringelike distortions, said electrodes being adapted to be connected to a source of constant potential.
2. A Braun tube comprising an envelope, a gas filling within said envelope, a cathode and an anode mounted in cooperative relation for producing a cathode beam in the order of at least 10^{-4} amperes, two pairs of deflecting plates, a picture receiving screen and two electrodes, each consisting of a thin metallic coating, said electrodes forming parts of an annulus and being mounted on the outer side of the wall of said envelope in parallel to the plates of one of said pairs of deflecting plates between said deflecting plates and said screen for preventing the occurring of fringelike distortions, said electrodes being adapted to be connected to a source of constant potential.

KURT SCHLESINGER.
